UNITED STATES PATENT OFFICE

110,921

DESIGN FOR A HANDBAG MIRROR

Jacob S. Fein, New York, N. Y.

Application June 7, 1938, Serial No. 77,644

Term of patent 7 years

To all whom it may concern:

Be it known that I, Jacob S. Fein, a citizen of the United States and resident of New York city, in the county and State of New York, have invented a new, original, and ornamental Design for a Handbag Mirror, of which the following is a specification, reference being had to the accompanying drawing, forming a part thereof, and of which top edge view thereof, Fig. 3 is a sectional view thereof taken on the line 3—3 of Fig. 1, and Fig. 4 is a view thereof in rear elevation.

The characteristic feature of the design resides in the marginal edges of the mirror back which project toward the mirror bevel, outwardly thereof.

I claim:

The ornamental design for a handbag mirror, substantially as shown and described.

JACOB S. FEIN.
